Primary Examiner — Keli L Hill(74) *Attorney, Agent, or Firm* — Stradley Ronon Stevens & Young, LLP(57) **CLAIM**

The ornamental design for a stackable plastic container, substantially as shown and described.

DESCRIPTION

FIG. 1 shows a side elevation view of the container with the top inlet opening on the right;

FIG. 2 shows a side elevation view of the container taken from the side opposite the side shown in FIG. 1, with the top inlet opening on the left;

FIG. 3 shows a top view of the container;

FIG. 4 shows a side elevation view of the container taken from a side adjacent the side shown in FIG. 1;

FIG. 5 shows a side elevation view of the container taken from a side adjacent to the side shown in FIG. 4 and opposite to the side shown in FIG. 1;

FIG. 6 shows a bottom view of the container;

FIG. 7 shows a perspective view of the top of the container; and,

FIG. 8 shows a perspective view of the bottom of the container.
